UNITED STATES PATENT OFFICE

ARNOLD BROBECK, OF BOMHUS, NEAR GEVLE, SWEDEN

METHOD OF HEATING CELLULOSE DIGESTING LIQUORS

Application filed February 14, 1929, Serial No. 339,944, and in Sweden February 18, 1928.

On directly heating liquors used for digesting cellulose-containing material said liquors have a tendency to form solid incrustations on the heating surfaces, which is a very great 5 inconvenience, as they considerably reduce the transmission of heat, cause interruptions in the manufacturing for cleaning purposes etc. It is especially on evaporating acid liquors for the sulphite cellulose method according to the indirect circulation method 10 that these inconveniences occur.

The inventor has found, that the reason of the formation of said incrustations on the heating surfaces is principally depending on 15 the fact, that the liquor has hitherto, principally due to improper construction of the heating apparatus, passed over the heating surfaces with too low a speed, which results in local superheating of the liquor.

The method forming the object of the present invention is based upon this observation, and the liquor is therefore in a special manner caused to pass along the heating elements 20 with a relatively high speed, and it has been found, that in this manner it has been possible 25 in practice to avoid the formation of incrustations on the heating surfaces.

According to the invention a relatively high number of heating elements are used 30 in the apparatus, and the invention is characterized by the fact, that the liquor is by means of special guiding members divided 35 into a great number of relatively thin streams, which are caused to move along the heating elements with a speed, which is, with regard 40 to the momentary conditions relating to the temperature of the heating medium and the composition of the liquor, so high that practically no incrustations are formed on the heating surfaces.

As heating medium steam is generally used, although it may also be possible to use other liquid or gaseous heating agents. The speed of the liquor along the heating surfaces 45 is, as previously set forth, dependent on the composition of the liquor and the temperature of the heating medium. As an example it may be set forth, that on evaporating sulphite digesting liquor with a content of 1.3% of 50 CaO and at a steam temperature of 185° C.

the speed of the liquor relatively to the heating surfaces ought to be about 2.5 meters per second. If the content of CaO is 1% and the steam temperature is 165° C., the speed of the liquor ought not to be lower than about 55 1.5 meters per second.

A form of an apparatus for executing the present invention is illustrated on the accompanying drawing, showing schematically an apparatus in vertical section, some parts being, however, shown in elevation.

1 designates a receptacle with walls 2 and 3. At one end said receptacle is provided with a cover 4 and tube plate 24, and between said plate and the wall 3 there is formed a chamber 5, which is provided with an outlet 26. At the opposite end of the receptacle there is a wall 6 located at a suitable distance from the wall 2, and between said walls there is formed a chamber 7, provided with an inlet 18. At a further distance from the wall 6 there is another wall 8, and between the walls 6 and 8 there is formed a chamber 9. This end of the receptacle is provided with a cover 10, and between the said cover and the wall 8 there is formed a chamber 11, which is provided with an inlet 12. The chamber 9 is provided with an outlet 13.

Longitudinally through the receptacle 1 there are located a number of tubes 14, extending between the walls 2 and 3, thus connecting the chambers 7 and 5 with one another.

Within these tubes there are located narrower tubes 15, which are closed at one end and extend from the wall 6 through the tubes 14. Their outer ends are supported by a tube plate 24, so that they are securely held in a central position with relation to the tubes 14. Within the tubes 15 are located narrower tubes 16 attached in the wall 8 and extending through the tubes 15 to the vicinity of the closed ends of the same. The tubes 16 are open at both ends.

From this construction it will be clear, that the tubes 16 communicate with the chamber 11. The tubes 15 communicate with the chamber 9, and the tubes 14 form a communication between the chambers 7 and 5.

Suppose that the apparatus in question is 100

used for indirectly heating sulphite digesting liquor according to the circulation method. The liquor is then introduced from the boiler (not shown) by aid of a pump or the like 5 through the conduit 18 into the chamber 7, from which the same is by means of a pump or the like caused to pass with a high speed through the intermediate space between the tubes 14 and 15 (the tubes 14 serving as 10 guides) and into the chamber 5 and from there through the outlet 26 and back to the boiler and from there again into the chamber 7 etc.

The quantity of the liquor introduced into 15 the apparatus is thus divided into a great number of relatively thin ring or tube-shaped streams surrounding the heating elements 15.

Steam is introduced through the conduit 12 into the chamber 11 and passes therefrom 20 through the tubes 16 against the bottoms of the tubes 15 and from there back through the tubes 15 to the chamber 9, from where steam and water of condensation are removed through the conduit 13. The tubes 15 thus 25 form the heating elements, and the liquor passes through the intermediate spaces between the tubes 15 and 14 with a relatively high speed. By this means local superheating of the digesting liquor is avoided and 30 consequently also the formation of incrustations on the heating surfaces.

By applying the present invention it has been found in practice, that it will be possible to avoid in an efficient manner the above 35 mentioned inconveniences on evaporating digesting liquors of the kind set forth.

The steam introduced into the chamber 11 generally has a temperature of more than 40 110° C., and generally it is convenient to maintain the liquor under a higher pressure when passing through the tubes 14, than it has in the boiler. This result can be obtained by throttling the outlet tube 26 by means of a valve or the like.

45 It is evident, that the above described apparatus can be modified in several ways without departing from the scope of the invention. So for instance it will be possible to place spiral-shaped guides in the intermediate spaces between the tubes 14 and 15 so as to cause the liquor to move along a spiral-shaped path. Nor is it necessary to have the tubes 14 and 15 located vertically, as they 50 may also have an oblique or horizontal position. The apparatus may also be so arranged, that the liquor is introduced into the upper part of the apparatus (chamber 5), in which case the closed ends of the tubes 15 must be turned in the opposite direction. It 55 is obvious that the outsides of the tubes 14 may also be heated by steam, so that the liquor layers are heated from two sides.

60 According to a known construction, which is also provided with a number of tubes, serving as heating elements, the liquor has been 65

caused to pass substantially across the heating elements, no guides being in this case provided to cause the liquor to pass in a great number of relatively thin streams along the heating elements. In said apparatus it has 70 therefore been impossible to avoid the formation of incrustations, although the liquid has passed with a relatively high speed through the apparatus.

Such evaporating methods are also known, 75 according to which the vapours, developed from the liquor, are compressed and again used as heating medium, the liquor being forced through tubes heated by said compressed vapours. This is, however, a special 80 case, which has nothing to do with heating methods of the kind described, as the said previous method has for its object to obtain a workable method in the special case, when the temperature-difference between the compressed heating vapours and the liquor is 85 only 2 or 3° C., in which case there is no risk for superheating the liquor in contact with the heating surfaces, and, consequently, much less risk for the formation of incrustations. 90

I claim:

The method of preventing the formation of incrustations on heating surfaces while conducting sulphite cellulose digesting liquor in contact with said heating surfaces, 95 consisting in dividing the liquor into a great number of relatively thin tube-like streams defined by said heating surfaces, applying heat at a temperature ranging from 110° C. to 185° C. to the inner surfaces of said tube-like streams, forcing said liquor streams at all points of travel at a velocity of at least 1.5 meters per second to thereby prevent boiling of the liquor and precipitation of monosulphite on the heating surfaces. 100

In testimony whereof I have hereunto affixed my signature.

ARNOLD BROBECK.
